(57) **CLAIM**

The ornamental design for a sheet with slits, as shown and described.

DESCRIPTION

FIG. 1 is a three-quarter profile view of showing the new design;

FIG. 2 is a top view thereof;

FIG. 3 is a bottom view thereof;

FIG. 4 is left side view thereof;

FIG. 5 is a right side view thereof;

FIG. 6 is front view thereof; and,

FIG. 7 is a back view thereof.

1 Claim, 4 Drawing Sheets(56)
